Variety denomination: 'KLEPZ17484'.

CROSS-REFERENCE TO RELATED
APPLICATIONS

A Canada Plant Breeders Rights application was filed on Mar. 27, 2017, Application No. 17-9151; a Switzerland Plant Breeders Rights application was filed on May 24, 2017, Application No. 17-3148; and a European Community Plant Variety Office application was filed on May 31, 2017, File No. 2017-1451. 'KLEPZ17484' has not been sold or made publicly available more than one year prior to the filing date of the instant application.

BACKGROUND OF THE NEW PLANT

The present invention comprises a new and distinct variety of *pelargonium*, botanically known as *Pelargonium zonale* and hereinafter referred to by the variety name 'KLEPZ17484'. 'KLEPZ17484' originated from a cross-pollination in September 2012 in Stuttgart, Germany between the female *pelargonium* variety 'SIL Magnus' (unpatented) and the male *pelargonium* variety PAC Abelina 'Pacabel' (U.S. Plant Pat. No. 22,881).

Seeds from the cross-pollination were obtained. The seeds were sown and plants were grown for evaluation. A single plant was selected in June 2013 and subsequently named 'KLEPZ17484'. In August 2013 'KLEPZ17484' was first vegetatively propagated by vegetative cuttings. 'KLEPZ17484' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

1. Large, red flowers on long peduncles; and
2. An upright, bushy, and round habit.
